Primary Examiner — Nathan M Johnston*(74) Attorney, Agent, or Firm* — Perkins Coie LLP**CLAIM**

The ornamental design for a catheter, as shown and described.

DESCRIPTION

FIG. 1 is a perspective view of a catheter showing my new design;

FIG. 2 is a front elevation view thereof;

FIG. 3 is a rear elevation view thereof;

FIG. 4 is a left side view thereof;

FIG. 5 is a right side view thereof;

FIG. 6 is a top plan view thereof; and,

FIG. 7 is a bottom plan view thereof.

The catheter is shown with a symbolic break in its length. The appearance of any portion of the article between the break lines forms no part of the claimed design.

The broken lines immediately adjacent the claimed areas represent the bounds of the claim, and all other broken lines are included for the purpose of illustrating portions of the design that form no part of the claimed design. None of the broken lines form part of the claimed design.
